Specification for Design.

Patented Nov. 27, 1917.

Application filed October 11, 1917. Serial No. 196,081. Term of patent 14 years.

To all whom it may concern:

Be it known that I, PHILIP K. WILLIAMS, a citizen of the United States, residing at Glastonbury, in the county of Hartford and State of Connecticut, have invented a new, original, and ornamental Design for a Cake of Soap, of which the following is a specification, reference being had to the accompanying drawings, forming part thereof.

Figure 1, is a plan view of a cake of soap embodying my new design.

Fig. 2, is a side elevation of the same.

Fig. 3, is a plan view of the side opposite to that shown in Fig. 1.

Fig. 4, is a central section thereof.

Fig. 5, is a view in cross section through the cake on plane located at right angles to the plane of section of Fig. 4.

I claim:

The ornamental design for a cake of soap as shown.

PHILIP K. WILLIAMS.
